SEPARATOR OF THE VORTEX TYPE FOR
PAPER PULP

Harold Eric Baliol Scott, London S. E. 1, England, assignor to Vickerys Limited, London, England, a company of Great Britain and Northern Ireland.

Application June 30, 1942, Serial No. 449,101
In Great Britain July 15, 1941

20 Claims. (Cl. 92—28)

This invention relates to separators for treating liquids and suspensions of solids in liquids, and more particularly for treating paper pulp, in which the material to be treated is injected tangentially at high speed through an inlet tapering to a reduced and substantially rectangular cross-section into a vortex vessel of circular section from which the purified material emerges in an upward direction while the separated impurities are allowed or encouraged to settle, preferably into a space sheltered from the swirl of the vortex chamber. Separators of this kind have been described in my application Serial No. 346,781.

Though capable of working satisfactorily over a wide range of conditions such separators work best at a particular speed of injection, that is to say at a particular angular velocity of the material to be treated. In practical conditions, however, the through-flow must often vary; the volume of pulp supplied to a paper machine will be changed with every change in the type of paper being made and in the consistency at which the pulp is being worked; also the pulp may be passing through a battery of two or more separators and one may have to be taken out of service through accidental clogging up or for some other reason, whereupon the through-flow of the remaining separators must substantially increase.

A primary purpose of this invention is to enable the separator to work at high efficiency over a wide range of through-flow by maintaining the speed of injection substantially constant notwithstanding variations in the through-flow. A subsidiary purpose is to enable manufacturers to satisfy by a small range of separators demands for separators for different through-flows extending over a wide range.

With these purposes in view one object of the invention is a vortex separator of the type above described which has means for constricting the inlet channel either in the inlet nozzle by which the material treated is injected or in the circular duct which continues the inlet nozzle and in which the vortex is formed. It is important that such means shall not disturb the formation of the vortex, as would occur if its outer layers should be directed inward across the vortex flow; the outer wall of the nozzle should therefore be continuous with the outer wall of the vortex-forming duct and constriction should be effected by modification of another wall bounding the inlet channel.

Wholly to achieve the aim of constant angular velocity involves increasing the head of supply as the flow diminishes, and therefore pulp should

be delivered to the separator by a pump having a slightly drooping pressure-output characteristic such as is readily obtained by suitable design in a centrifugal pump. A rise of from 5 to 6% in the pressure has been found sufficient to cover a range of output from full load to $\frac{1}{2}$ full load.

For the purpose of adapting a given design of separator to any fixed through-flow within a small range the necessary constriction of the inlet channel may be effected once for all at the factory. To suit a separator to the varying through-flow occurring in the paper factory the means for constricting the inlet channel must be under the control of the user. A further object of the invention is a separator in which the area of cross-section of the inlet channel at its smallest is controlled automatically in accordance with the through-flow. More specifically, an object of the invention is a vortex separator with means for constricting its inlet channel governed by a float adjacent to a weir in one of the conduits by which the material treated is led to and from the separator.

For very wide variations of the through-flow it may be desirable to vary the area of the outlet also in the same sense as the through-flow. Varying the area of outlet as the inlet flow area is varied in accordance with variations of through flow, tends to control pressure within the vessel which influences the effective length of the vortex. Yet another object of the invention, therefore, is a separator having interconnected means of varying the cross-sectional area of both the inlet channel and the outlet conduit.

35 Further objects of the invention will appear from the detailed description following.

A number of possible constructions of variable inlet for the purpose of the invention are illustrated in the accompanying drawings:

40 Figures 1 and 2 are elevation and plan respectively, each partly in section, of the head of a vortex separator having both a variable inlet and a variable outlet;

45 Figure 3 is an elevation in section on the line 3—3 of Figure 4, and Figure 4 a plan in section on the line 4—4 of Figure 3 of a modified construction;

Figure 5 is an elevation of the movable part of the variable inlet of Figures 3 and 4;

50 Figure 6 is an axial section and Figure 7 a plan in section on the line 7—7 of Figure 6 of an alternative construction of variable outlet, while Figure 8 is similar to Figure 7 but shows the parts in a different relative position, and Figure 9 is an elevation in section on the line 9—9 of Figure 8.

Figure 10 is a sectional plan of a third form of variable inlet, in which, as in the constructions so far mentioned, the constriction affects the radial depth of the inlet;

Figure 11 is a plan from underneath, in section on the line 11-11 of Figure 12, and Figure 12 is an elevation in section on the line 12-12 of Figure 11, (the tangential inlet however being shewn in axial section,) of a fourth form of variable inlet.

Figure 13 is an elevation partly in section of a fifth form of variable inlet which, like the fourth, is variable in effective axial depth.

Figure 14 is a diagram illustrating the automatic control of a variable inlet, or inlet and outlet.

In all the constructions 1 is the upper part of the main portion of the vortex vessel proper, and 2 a head bolted on to it of which the tapered tangential inlet nozzle 3 is a part and within which is the helical path through which the suspension reaches the vortex vessel; an outlet pipe 4 is bolted to the upper flange of the head 2. In Figures 1 and 2 the outlet pipe 4 projects downward into the vortex vessel a sufficient distance to ensure the desired separation of impurities taking place before the suspension is permitted to turn in an upward direction. Between the flange of the outlet pipe and that of the head there is located and secured the flange of a sleeve 5, a fluid-tight joint being made between the flanges by suitable packing in annular grooves 6. This sleeve forms a portion of the outlet and fits and fills the cylindrical and concentric portions of the upper part of the vessel formed in the head 2 above a circumferential groove in the sleeve. This groove is of increasing radial depth and of the same axial depth as the tangential inlet nozzle 3; this is annular at its top and thereafter helical. The groove deepens to the full radial thickness of the sleeve, which therefore ends in a helical tail 7 wrapped around the outlet pipe. An arm 8 projecting from the sleeve 5 has bolted to it a toothed segment 9 with which meshes a pinion 11 on a vertical shaft 12 supported at its upper end in a bracket 13 secured by the bolts which fasten the head 2 to the vortex vessel 1. At a convenient height lower down the shaft 12 may carry a hand-wheel 14 as appears from Fig. 14, or as hereinafter described with reference to that figure it may be equipped with automatic operating means.

Figures 1 and 2 also show a means for adjusting the effective cross-sectional area of the outlet pipe 4 in correspondence with and simultaneously with the adjustment of the inlet. For this purpose a rounded plunger 15 is mounted to slide in a gland 16 in the wall of the outlet pipe 4. There is attached to it a pin carrying a roller 17 located in a cam slot 18 in a cam member 19 secured to the arm 8.

By turning the shaft 12 by the aid of the handwheel 14 or otherwise the sleeve 5 may be turned either way from the mid position shown in the figures. If it is turned anti-clockwise as seen in Fig. 2 until the point 21 on the sleeve registers with the point 22 on the head 2, the inlet will have its maximum cross-section. In the position shown the inlet is substantially contracted, without sudden change of cross-section and without disturbance of the outer layers of the suspension. The constriction is at all times close to the beginning of the circular path, so that the increased speed imparted by the constriction is effective in the formation of the vor-

tex. The tail piece 7 is deepened where necessary to prevent any part of the inlet port of the head being uncovered clear of the sleeve 5 in the end position of the latter. The turning of the sleeve 5 also causes the cam 19 to advance the plunger 15 into or withdraw it from the outlet pipe 4 so that the cross-section of the inlet is diminished or increased.

If it is not intended that the user shall have the facility of adjusting the separator to a varying through-flow the arm 8, and adjusting mechanism 9, 11, 12, 13, 14 are not required; nor is the packing between 2, 4 and 5. The sleeve 5 is set once and for all by the manufacturer to correct for any tolerance in manufacture affecting the through-flow, or to adjust the through-flow to a particular value within a limited range, and is then fixed in position and the parts bolted up tight.

In the modification shown in Figs. 3, 4 and 5 the outlet pipe proper 4 ends at its flange and is prolonged by the inlet-regulating sleeve 23; the upper part of the sleeve is, as before, of a diameter equal to that of the head, and in this part is formed a helical groove as already described. The bore of the sleeve, equal to that of the outlet pipe at the top, is constricted at 24; above this constriction a rod 25 with an enlarged and tapered end 26 is mounted to slide in a gland 27 in the outlet pipe 4; it is moved by a bell-crank lever 28 pivoted on a bracket 29 on the outlet pipe and rocked by the action of the cam 19 upon a roller 31 on its end.

The form of the sleeve 23 is further illustrated in Figure 5 on which are indicated the relative position of the port 20 in the head when the inlet is reduced to minimum cross-section, and the extension 30 of the full diameter part of the sleeve 23 necessary to keep the port wholly covered by the sleeve.

Figures 6 to 9 show an alternative means of varying the cross section of the outlet. In the end of the outlet pipe 4 there is a cross-bar 32 of stream-lined cross-section and spindle shaped. There is a similar bar 33 in the sleeve 34 with its flat side uppermost and in contact with the bar 32. In the position shown in Fig. 6 the one bar exactly covers the other and the two offer the least obstruction to the flow. When the sleeve 34 is turned the two bars take up such a relative position as is shown in Figs. 8 and 9, in which the free area of bore of the outlet pipe is reduced substantially to the minimum. By suitable design of the bars 32 and 33, which may have other forms than that shown, the variation of bore from maximum to minimum may be made to occur over the same arc of turning as is needed to change from maximum to minimum area of inlet.

In Fig. 10 is shown another way of contracting radial width of the inlet so as to secure a high speed flow in the outer layers of the stream without disturbing their course. In a gland 35 in the side of the head 2 and on the inner side of the inlet, there is mounted a sliding bar 36 having a bevelled end. A screw 37 engaging the forked outer end of the bar serves as a means of adjusting it so that either, as shown in full lines, its surface is practically a continuation of the fixed surface of the inlet, or, as shown in dotted lines, it projects more or less into the inlet constricting it radially. In either position its surface makes an angle of not much less than 180 degrees with the adjacent fixed parts of the channel, so that there are no recesses in which the

solid matter of the suspension treated can accumulate sheltered from the sweep of the stream.

It is also possible to restrict the inlet channel by lessening its axial depth. A construction so operating is shown in Figs. 11 and 12. Between the adjacent flanges of the vortex vessel 1 and the head 2 there is mounted a flat plate 38, located by annular ribs engaging in grooves in the flanges and turned by an arm 39 in the same manner as the sleeve of Figs. 1 and 2. The head 2 is here shown as integral with the outlet pipe 4, and its helical channel is seen in Figure 12 to be more or less obstructed by plate 38 according as the plate is turned in one direction or the other.

The same effect is obtained in the construction shown in Fig. 13 by making one wall of the helical channel in the head from a resilient helical strip 41. Its upper end is secured to the head, while its lower end is recessed and rests upon a pin 42 projecting from the outlet pipe 43, which is made to slide vertically in the head 2. A rack 44 upon the pipe and a pinion 45 engaging it serve for adjusting the inlet, the pinion being turned by hand or automatically like the shaft 12 of Figs. 1 and 14. Chain dotted lines indicate the effect of the inlet of raising the outlet pipe.

As a rule it will be sufficient to adjust the inlet by hand. If any guidance is needed as to the proper adjustment it may be given by an indicator operated by a float resting on the stream of suspension treated adjacent to a weir over which it flows in its passage to or from the separator. This is diagrammatically illustrated in Fig. 14. The mixing box is shown at 46 with pipes 47 and 48 conveying to it backwater and stock respectively. A pump 49 draws pulp from the mixing box 46 and delivers it to one or more vortex vessels 1. The pump should preferably have a slightly drooping pressure-output characteristic, for to obtain constant angular velocity in the vortex vessel involves increasing the head of supply as the flow diminishes. The purified pulp delivered by the separator 1 into the flow box 51 is maintained in excess of the demands of the paper-making machines which the separators serve, and the surplus returns to the mixing box over a weir 52. Adjacent to this weir a float 53, which may be in the form of a wheel or roller and may be rotated by a motor 54, rests on the surface of the stream. It is shown as carried on a radial arm 55 to which is attached a pointer 56 moving over a scale.

If it is desired to make the adjustment of the inlet automatic the same float may govern the action of a servo motor for that purpose. As shown the motor 54 through an eccentric rocks a pivoted arm 57 carrying two pawls 58, 59, either or both of which may be held out of engagement with a toothed wheel 61 by a rocking cam 62 linked to the float 53. As soon as a fall or rise in the level of the overflowing pulp permits one of the pawls to engage the wheel 61 the wheel is turned step by step, and through a chain and gearing turns the shaft 12 in the direction to increase or diminish the inflow into the separator as may be necessary to restore the overflow to its original level. There may also be a cam rotated with the wheel 61 to lift the pawl 58 or 59 out of engagement when the limit of adjustment has been reached.

Where several vortex separators are operating in parallel their means of adjustment may be coupled so that the load is at all times equally distributed among them.

When an auxiliary or secondary separator is used for giving further treatment to the impure pulp withdrawn from the primary separators, as described in my above mentioned specification, the variable inlet of the auxiliary separator may be used to control the amount of pulp withdrawn.

I claim:

1. A vortex separator comprising a vortex vessel of circular cross-section, an outlet conduit extending upward out of said vessel from a point intermediate in its length and with the upper part of the wall of the vortex vessel bounding an annular vortex-forming duct, an inlet nozzle tapering to a reduced and substantially rectangular cross section joining said annular duct tangentially near its top and forming therewith an inlet channel, the outer wall of said nozzle being continuous on its inner surface with the outer surface of said duct, and means constituting part of another wall of said inlet channel movable to constrict said inlet channel while maintaining a gradual curvature of said inner wall in all positions of adjustment and without disturbing the forming of the vortex.

2. Apparatus for purifying paper pulp including a vortex separator as in claim 1 having movable wall means for varying the size of the incoming stream of flow, means responsive to variations in the rate of flow of pulp through said separator, and means controlled by said responsive means to actuate said varying size means.

3. Apparatus for purifying paper pulp including a vortex separator as in claim 1 having movable wall means for varying the size of the incoming stream of flow, means responsive to variations in the rate of flow of pulp through said separator, a servo-motor, and means controlled by said responsive means to render said servo-motor effective to actuate said varying means in a direction to decrease the departure of such response from a predetermined value.

4. A vortex separator comprising a vortex vessel of circular cross-section, an outlet conduit extending upward out of said vessel from a point intermediate in its length and with the upper part of the wall of the vortex vessel bounding an annular vortex-forming duct, an inlet nozzle tapering to a reduced and substantially rectangular cross section joining said annular duct tangentially near its top and forming therewith an inlet channel, the outer wall of said nozzle being continuous on its inner surface with the outer surface of said duct and means constituting part of the inner wall of said inlet channel movable to reduce the radial depth of said channel while maintaining a gradual curvature of said wall.

5. A vortex separator comprising a vortex vessel of circular cross-section, an outlet conduit extending upward out of said vessel from a point intermediate in its length and with the upper part of the cylindrical and concentric wall of the vortex vessel bounding an annular vortex-forming duct, said conduit fitting and filling a cylindrical and concentric portion of the upper part of said vortex vessel and having in its outer surface a groove of increasing radial depth which with the wall of the vortex vessel constitutes the vortex-forming duct, an inlet nozzle tapering to a reduced and substantially rectangular cross section joining said vortex-forming duct tangentially and forming therewith an inlet channel, and means for turning said conduit to vary the minimum radial depth of the inlet channel.

6. A vortex separator comprising a vortex ves-

- sel of circular cross-section, an outlet conduit extending upward out of said vessel from a point intermediate its length and with the upper part of the wall of the vortex vessel bounding an annular space, an inlet nozzle tapering to a reduced and substantially rectangular cross-section joining said annular space tangentially near its top and forming therewith an inlet channel, the outer wall of said nozzle being continuous on its inner surface with the outer surface of said space, and a sleeve rotatable upon said outlet conduit within the vortex vessel, the outer surface of said sleeve being in part of diminishing radius, diminishing in a circumferential direction, whereby rotation of said sleeve varies the minimum radial depth of the vortex-forming duct formed between said sleeve and the wall of the vortex vessel.
7. A vortex separator comprising a vortex vessel of circular cross-section, an outlet conduit extending upward out of said vessel from a point intermediate in its length and with the upper part of the wall of the vortex vessel bounding an annular vortex-forming duct, an inlet nozzle tapering to a reduced and substantially rectangular cross-section joining said annular duct tangentially near its top and forming therewith an inlet channel, the outer wall of said nozzle being continuous on its inner surface with the outer surface of said duct, means constituting part of another wall of said inlet channel movable to constrict said inlet channel without disturbing the forming of the vortex and means mechanically connected with said movable part of the inlet channel wall for correspondingly constricting said outlet conduit.
8. Apparatus for purifying paper pulp including a vortex separator as in claim 7 having movable wall means for varying the size of the incoming and outgoing streams of flow, means responsive to variations in the rate of flow of pulp through said separator, and means controlled by said responsive means to actuate said varying size means.
9. Apparatus for purifying paper pulp including a vortex separator as in claim 7 having movable wall means for varying the size of the incoming and outgoing streams of flow, means responsive to variations in the rate of flow of pulp through said separator, a servo-motor, and means controlled by said responsive means to render said servo-motor effective to actuate said varying means in a direction to decrease the departure of such response from a predetermined value.
10. A vortex separator comprising a vortex vessel of circular cross-section, an outlet conduit extending upward to the top of, out of said vessel from a point intermediate in its length and with the upper part of the cylindrical and concentric wall of the vortex vessel bounding an annular vortex-forming duct, said conduit fitting and filling a cylindrical and concentric portion of the upper part of said vortex vessel and having in its outer surface a groove of increasing radial depth which with the wall of the vortex vessel constitutes the vortex-forming duct, a transverse obstruction at the upper end of said conduit, an outlet pipe secured upon said vortex vessel and continuing said outlet conduit, a transverse obstruction at the end of said pipe adjacent to the outlet conduit, an inlet nozzle tapering to a reduced and substantially rectangular cross section joining said vortex-forming duct tangentially and forming therewith an inlet channel, and means for rotating said conduit to vary the minimum radial depth of the inlet channel, and to cause said obstructions to overlap to a greater or less extent.
11. A vortex separator comprising a vortex vessel of circular cross-section, an outlet conduit extending upward out of said vessel from a point intermediate in its length and with the upper part of the wall of the vortex vessel bounding an annular space, an inlet nozzle tapering to a reduced and substantially rectangular cross section joining said annular space tangentially near its top and forming therewith an inlet channel, the outer wall of said nozzle being continuous on its inner surface with the outer surface of said space, a sleeve rotatable upon said outlet conduit within the vortex vessel, the outer surface of said sleeve being in part of diminishing radius, diminishing in a circumferential direction, whereby rotation of said sleeve varies the minimum radial depth of the vortex-forming duct formed between said sleeve and the wall of the vortex vessel an obstruction reciprocable across said outlet conduit to vary its area of cross-section, and a cam rotatable with said sleeve and acting on said obstruction to reciprocate it.
12. A vortex separator comprising a vortex vessel of circular cross-section, an outlet conduit extending upward out of said vessel from a point intermediate in its length and with the upper part of the wall of the vortex vessel bounding an annular vortex-forming duct, an inlet nozzle tapering to a reduced and substantially rectangular cross-section joining said annular duct tangentially near its top and forming therewith an inlet channel, the outer wall of said nozzle being continuous on its inner surface with the outer surface of said duct, and means for varying the axial depth of said inlet channel.
13. A vortex separator comprising a vortex vessel of circular cross-section, an outlet conduit extending upward out of said vessel from a point intermediate in its length and with the upper part of the wall of the vortex vessel bounding an annular vortex-forming duct, an inlet nozzle tapering to a reduced and substantially rectangular cross section and having a helical end merging into said annular duct tangentially near its top and forming therewith an inlet channel, the outer wall of said nozzle being continuous on its inner surface with the outer surface of said duct, a plate prolonging the bottom of said helical end of the inlet nozzle at an angle to its top, and means for shifting said plate in its own plane to vary the effective cross-section of said inlet channel.
14. A vortex separator comprising a vortex vessel of circular cross-section, an outlet conduit extending upward out of said vessel from a point intermediate in its length and with the upper part of the cylindrical and concentric wall of the vortex vessel bounding an annular vortex-forming duct, an inlet nozzle tapering to a reduced and substantially rectangular cross-section and having a helical end merging into said annular duct tangentially near its top and forming therewith an inlet channel, the outer wall of said nozzle being continuous on its inner surface with the outer surface of said duct, and the bottom wall of said nozzle continuing as a resilient helix forming a partition across said vortex-forming duct, means engaging the end of said helix with said outlet conduit, and means for shifting said outlet conduit axially to alter the pitch of said

helix and the axial depth of the vortex-forming duct.

15. Apparatus for purifying paper pulp including a vortex separator, conduits conveying pulp to and from said separator, said separator comprising a vortex vessel of circular cross-section, an outlet conduit extending upward out of said vessel from a point intermediate in its length and with the upper part of the wall of the vortex vessel bounding an annular vortex-forming duct, an inlet nozzle tapering to a reduced and substantially rectangular cross section joining said annular duct tangentially near its top and being continuous on its inner surface with the outer surface of said duct, means constituting part of another wall of said inlet channel movable to constrict said inlet channel without disturbing the forming of the vortex, a weir in one of the conduits conveying pulp to and from said separator, a float resting on the surface of the pulp adjacent said weir, and means governed by said float for shifting the movable part of the wall of said inlet whereby the area of inlet is adjusted to the through-flow with which the separator has to deal.

16. A vortex separator comprising a vortex vessel of circular cross-section, an outlet conduit extending upward out of said vessel from a point intermediate in its length and with the upper part of the cylindrical and concentric wall of the vortex vessel bounding an annular vortex-forming duct, said conduit fitting and filling a cylindrical and concentric portion of the upper part of said vortex vessel and having in its outer surface a groove of increasing radial depth which with the wall of the vortex vessel constitutes the vortex-forming duct, and an inlet nozzle tapering to a reduced and substantially rectangular cross section joining said vortex-forming duct tangentially and forming therewith an inlet channel.

17. A vortex separator comprising a vortex vessel of circular cross-section, an outlet conduit extending upward out of said vessel from a point intermediate in its length and with the upper part of the wall of the vortex vessel bounding an annular space, an inlet nozzle tapering to a reduced and substantially rectangular cross-sec-

tion joining said annular space tangentially near its top and forming therewith an inlet channel, the outer wall of said nozzle being continuous on its inner surface with the outer surface of said space, and a sleeve upon said outlet conduit within the vortex vessel, the outer surface of said sleeve being in part of diminishing radius, diminishing in a circumferential direction to delimit the inlet channel within said annular space.

18. Apparatus for purifying paper pulp, said apparatus including a vortex vessel of circular cross section, an inlet portion for said vessel having means for varying the cross sectional size of the stream of pulp entering said vessel, means responsive to the rate of flow through said vessel, and means controlled by said responsive means to actuate said varying size means to vary the size of the stream with varying rate of flow through the vessel to tend to maintain the velocity of flow of said stream into said vessel at a desired value.

19. Apparatus for purifying paper pulp, said apparatus including a vortex vessel of circular cross section, an inlet portion for said vessel having means for varying the cross sectional size of the stream entering said vessel, an outlet conduit for said vessel having means for varying the size of the outlet stream from said vessel, means responsive to the rate of flow through said separator, and means controlled by said responsive means to adjust both of said stream size adjusting means in accordance with varying rates of flow to tend to maintain the velocity of flow of said stream into said vortex vessel and the pressure within said vessel at desired values.

20. Apparatus including a vortex vessel of circular cross section, an inlet portion for said vessel having means for varying the cross sectional size of the stream of pulp entering said vessel, said vessel having an outlet, a tank provided with a weir and arranged in the flow of pulp which includes said vortex vessel, a float in said tank, and means responsive to changes of level of said float to control said varying means in a direction to tend to maintain the level of said float constant.

HAROLD ERIC BALIOL SCOTT.
